FOLDING CHAIR SEAT FASTENER

Willard G. Axtell, Denver, Colo., and Darold T. Beggs and Diamond A. Amorose, Lincoln Park, Mich., assignors to Shwayder Brothers, Denver, Colo., a corporation of Colorado

Application March 2, 1953, Serial No. 339,758

2 Claims. (Cl. 155—196)

This invention relates to tables, and more particularly to a table top mounting.

It is the object of the present invention to provide a novel means of securing a platform upon a tubular frame.

It is the further object of this invention to utilize this novel means in a table construction.

It is the further object of this invention to provide this novel means in a chair construction.

It is the still further object of this invention to provide a simplified yet effective device for securing a table top upon a tubular frame in such fashion that it may be removed, if desired, for replacement or repair.

These and other objects will be seen from the following specification and claims in conjunction with the appended drawings, in which:

Fig. 1 is a fragmentary side elevational view of a card table with the legs broken away.

Fig. 2 is a section taken on line 2—2 of Fig. 1.

Fig. 3 is a section taken on line 3—3 of Fig. 2.

Fig. 4 is a plan view illustrating the table top fastener as pivotally mounted upon the table top, which is fragmentarily shown.

Fig. 5 is a side elevational view thereof.

Fig. 6 is a right end elevational view thereof.

Fig. 7 illustrates the present fastening device in conjunction with a tubular frame of slightly different construction.

Fig. 8 is an elevational view illustrating a slightly different type of fastening device for the table top.

Fig. 9 is a left side elevational view thereof.

Fig. 10 is a fragmentary elevational section similar to Fig. 8 illustrating a slightly different form of fastener.

Fig. 11 is a side elevational view of a chair utilizing the present fastening device for the chair platform upon the tubular seat frame.

Fig. 12 is a section taken on line 12—12 of Fig. 11.

Fig. 13 is a fragmentary elevational section illustrating the securing of the seat platform to the seat frame; and

Fig. 14 is a section taken on line 14—14 of Fig. 13.

It will be understood that the above drawings illustrate merely several preferred embodiments of the invention and that other embodiments are contemplated within the scope of the claims hereafter set forth.

Referring to the drawings, a table is generally indicated at 11 having a hollow rectangular tubular frame 12, which is of substantially elliptical shape in cross-section, the corners of said rectangular frame being rounded at 13.

Said tubular frame includes an inner substantially upright wall 14, an outer convex wall 15 and top and bottom arcuate edges 16 and 17 constructed of a radii less than the radius of outer wall 15.

The rectangularly shaped top 18 is positioned upon the top arcuate edge 16 of tubular frame 12 and is secured thereto by the pivotal clips 25 in the manner hereafter described.

Arranged in each of the corners 13 of frame 12 and suitably secured thereto, as by welding, are leg mounting brackets 19 with inwardly directed U-shaped extensions 20 within which the respective legs 21 are pivotally mounted at their upper ends. The slotted stay 22 is

2

pivotedly connected at one end to the frame and receives within its slot the headed pin 23 which projects from leg 21 in a conventional manner.

Throughout the interior surface of frame 12 in the flat wall portion 14 thereof are a plurality of longitudinally spaced longitudinally extending slots 24 adapted to have swung thereto the offset projections 28 of the table top locking clips 25, which are positioned upon the undersurface of said table top and pivotally joined thereto as by the rivets 26, Fig. 3.

Clip 25 towards its outer end has an upright wall 27 which terminates in the offset clip end 28 as shown in Fig. 3. It will be noted that the side edge 29 of clip 25 is shorter than the side edge 30, so that the clip wall 27 at the upper end thereof, as in Fig. 4, is closer to pivot 26 than the other end of said upright wall 27. It therefore follows that the upright wall 27 lies in a plane at an acute angle to the longitudinal axis of clip 25, as indicated at 31, Fig. 4, to thereby facilitate the rotation of clip 25 and the introduction of the clip end 28 within the slot 24.

By this construction, when the clip 25 is at right angles to the adjacent wall portion of the frame 12, the outer surface of upright element 27 as at point 33 operatively engages the outer upright wall portion 14 of said frame adjacent slot 24.

As shown in Figs. 5 and 6, the offset clip end 28 is inclined forwardly and upwardly as indicated in 32 whereby as said clip end is introduced into slot 24 the lower edge 32 will frictionally and operatively and wedgingly engage the lower bounding wall defining slot 24.

By this construction, the clip when rotated to the position shown in Fig. 3 tightly draws up table top 18 against the top edge 16 of frame 12.

It will be noted that the clips 25 are initially secured to the undersurface of table 18 and swivelled thereon by the rivets 26 and are in engagement with the undersurface of top 18.

Referring to Fig. 7, there is shown a slightly different cross-sectional shape of tubular table frame which includes the convex outer surface 34, rounded top surface 35, inwardly directed shoulder portion 36, upright inner wall portion 37 and rounded bottom edge 38. The table top 39 has swivelled thereunder a plurality of clips 40 joined thereto by the rivets 41, which clips are substantially the same as the clips 25 above described with respect to Figs. 4, 5 and 6. Said clips include the downwardly extending upright wall 42, which terminates in the outwardly projecting clip end 43 which operatively engages under the shoulder 36 of the frame shown in Fig. 7. The upright wall 42 upon its outer surface operatively engages the internal portion of frame element 35, and at the same time the clip end 43 wedgingly engages shoulder 36 when said clip is rotated so as to be at right angles to the adjacent wall 37 of said tubular frame.

This construction is similar to the frame construction above described except that the slots 24 are omitted and substituted therefore is the shoulder formation 36.

Figs. 8 and 9 also show a slight variation in a clip construction for securing table top 50 to the tubular frame shown in Fig. 8. Said frame includes the convex outer surface 44, top and bottom arcuate edges 45 and 46 and the inner upright wall 47 which has a plurality of longitudinally spaced slots 48 formed therein.

The securing clip 49 is positioned upon the undersurface of top 50 and pivotally joined thereto by rivet 50'. Clip 49 has right angular depending portion 51 with an inturned lip 52 at its free end to facilitate the downward positioning of the respective clip elements 51 into the hollow rectangular formed frame. Within the depending clip element 51 there is provided a struck out

portion 53 cut out from element 51 on three sides and bent outwardly as at 53 in Fig. 8 and adapted for cooperative retaining positioning within the respective transverse slot 48 formed in the inner wall 47 of said frame.

Once the locking elements 53 are within the said slots, the top 50 may not be removed from said frame without manually bending clips element 51 inwardly sufficiently as to disengage locking element 53 from the top bounding wall, which defines transverse slot 48.

Fig. 10 illustrates still another variations of the clip shown in Fig. 8. The clip 55 is swivelly mounted upon the undersurface of top 54 by the rivet 56. Said clip has a downwardly depending portion 57 and a formed struck out element 60 with an outturned end portion 61, which extends through the transverse slot 59 formed in clip element 57 by the striking out of the lock element 60—61. Here also said clip element has an inturned lip 58 similar to lip 52 of Fig. 8 to facilitate insertion of clip element 57 within the frame. The locking end 61 projects beyond the upright wall of clip element 57 and is adapted for cooperation and retaining positioning within a transverse slot in the inner wall of the frame, such as slot 48 of Fig. 8.

The present invention broadly pertains to a novel securing of any type of platform to a tubular frame utilizing the clip element rotatably supported upon the undersurface of the platform and having a projecting portion adapted to be engaged within a slot or other formation of the tubular frame.

While Figs. 1-10 illustrate the application of the invention to a card table construction or other table, Figs. 11-14 illustrate an embodiment of the invention when incorporated into a folding chair.

Such a chair includes the inverted U-shaped tubular frame 63 terminating in the spaced front legs 64 and 65, there being a formed back rest 66 secured within the upper portion of said frame.

A substantially rectangular seat, generally indicated at 67, is positioned between the legs 64 and 65 and pivotally joined thereto by the transverse rivets 72. The seat 67 includes the U-shaped tubular frame 68, the free ends of which have caps 69. The free ends are interconnected by the cross bar or strip 70 whose ends are projected into corresponding transverse apertures 71 adjacent the caps 69. Rivets 72 extend through legs 64 and 65 and through corresponding adjacent portions of the tubular frame 68 upon opposite sides of said seat and intermediate its front and rear edges.

There are also provided a pair of upright rear legs 73 and 74 arranged at an acute angle respectively to front legs 64 and 65, in advance of said legs or lying in substantially the same plane. Said legs adjacent their upper ends and upon their interior surfaces having secured thereto the mounting brackets 73' which pivotally connect as by the rivets 74' rear portions of tubular frame 68. Caps 75 are provided for the upper ends of said rear legs, and in the fully opened position of the chair shown in Fig. 11, said caps operatively engage the undersurface of 64 and 65.

Links 76 are pivotally connected at their one ends at 77 to legs 73 and 74 and at their other ends are pivotally connected at 78 to the front legs to complete the chair assembly.

A substantially rectangular seat platform 79 is positioned upon the top surface of frame 68 as shown in Fig. 11.

Referring to Fig. 13, the frame 68 has an outer convex surface and top and bottom arcuate edges 81 and 80 respectively and an inner upright wall portion 82.

Said wall portion 82 has at spaced points thereon a plurality of horizontally extending slots 83 which are adapted to cooperatively receive the offset ends 90 of the clips 84.

Said clips are rotatably positioned against the undersurface of platform 79 and secured thereto by the rivets

85, so that the clip ends 90 will be cooperatively and retainingly positioned within slots 83 of frame 68 when said clips are at right angles to an adjacent portion of said frame, as in Fig. 14.

Clip 84 has toward one end the upright wall portion 86 which is so formed as to be arranged at an acute angle to the longitudinal axis of clip 84 inasmuch as the side edge 87 is shorter than the opposite side edge 88. This inclination of the substantially upright wall 86 provides the clearance opening 89 to facilitate rotation of clip 84 so that the clip end 90 enters slot 83 and so that a portion of the upright wall 86 will operatively engage wall portion 82 of said frame when the clip is in the position shown in Fig. 14.

Furthermore, the clip end 90 is inclined as at 91 whereby upon adjusting said clip to the position shown in Fig. 13, the trailing undersurface of clip end 91 will operatively and wedgingly engage the wall portion of said frame, which defines the slot 83, to thereby tightly draw up the platform 79 against the top edge 81 of the tubular frame 68.

The rear undersurface portion of platform 79 is secured to the strip 70 by a pair of right angular clips 92 riveted at 93 to the undersurface of platform 79 and riveted at 94 to said strip.

Having described our invention reference should now be had to the claims which follow for determining the scope thereof.

We claim:

- 30 1. In a folding chair having a pair of front legs, a pair of rear legs and a seat between said pairs of legs and pivotally mounted thereon, said seat comprising a hollow tubular frame lying in a single plane, said frame having a plurality of spaced horizontally extending coplanar slots 35 formed in its inner wall, a platform positioned upon said frame, and a plurality of locking clips pivotally secured upon the under surface of said platform adjacent said frame, each clip being vertically offset below said platform extending horizontally through and retainingly positioned in an adjacent frame slot, the offset end of each clip lying in a plane inclined laterally to the plane of said clip for wedging engagement with a portion of said frame forming the top boundary of the slot for drawing up said platform into tight engagement with said frame.
- 40 2. The combination of claim 1, there being an upright wall on each clip joining said offset, and said wall operatively engaging the outside wall of said frame adjacent said platform when said clips are in platform locking position at right angles to the corresponding inner wall 45 of said frame.
